UNITED STATES PATENT OFFICE.

JOHN REBEL, OF CLEVELAND, OHIO.

BATH-TUB BRUSH.

1,182,038.

Specification of Letters Patent.

Patented May 9, 1916.

Application filed July 1, 1915. Serial No. 37,423.

To all whom it may concern:

Be it known that I, JOHN REBEL, a citizen of the United States, residing at Cleveland, in the county of Cuyahoga and State of 5 Ohio, have invented certain new and useful Improvements in Bath-Tub Brushes, of which the following is a specification.

This invention pertains to a brush for bathtubs, and the invention consists in the 10 construction and combination of parts substantially as shown and described and particularly pointed out in the claims.

In the accompanying drawings, Figure 1 is a perspective view of the brush and its 15 handle strap. Fig. 2 is a cross section thereof. Fig. 3 is an enlarged view of the brush and a cross section of a portion of a bathtub to which it is removably attached over the roll thereon.

20 The invention thus shown covers a convertible bath brush B, the said brush being, preferably, constructed with a rubber back or body, and provided with a unitary flexible handle strap 2 provided with a link 3 in its free end and a hook *h* swiveled in said link so as to freely turn therein according to the engagement to be made therein. Thus, the brush is provided with a lip or 25 slot adapted to engage the hook *h* therein and to frictionally hold the hook when engaged, as the tendency would otherwise be for the hook to drop out when the handle was relaxed. The said hook also has 30 more or less flexibility or spring so as to engage and lock over or upon the roll 6 of the bath tub T. In this latter position the brush lies against the end of the inside of the tub and provides a head rest for the bather, 35 while in the relation of the parts in Fig. 1, the strap 2 engages over the hand like hand straps usually in brushes. By means of the swivel the hook can be reversed so as to turn 40 inward as in Fig. 1 compared with the reverse position in Fig. 3. That is, without

the swivel the hook would have to be engaged from within outward instead of from without inward as in Fig. 1, and that would be both awkward and otherwise undesirable. The spring of the hook adapts it to rolls of 50 different sizes within limits. The strap or handle 2 is almost necessarily made of rubber, but if other desirable flexible material be substituted for the rubber it will be with- 55 in the invention. Brush B is also shown as made of rubber but it may be constructed of other material. However, rubber is pre- 60 ferred as it provides a member capable of serving as a cushion and also furnishes a flexible strap 2 adapted to conform to the curvature of the roll to permit engagement of the hook *h* with the edge thereof.

What I claim is:

1. A bath-tub brush having a strap affixed to one edge thereof and a spring hook having swiveled connection with the other end and provided with a catch for said hook, whereby said hook can be engaged with said catch or with the roll of a bath-tub at pleasure. 65

2. A bath-tub brush having a flexible strap permanently engaged with one edge thereof and provided with a hook rotatably attached to the other end and adapted to be engaged over the roll of a bath tub, and 70 means on the opposite edge of the brush 75 adapted to engage said hook therewith.

3. An article of manufacture consisting of a bath-tub brush having a flexible strap attached to the edge thereof and provided with a hook rotatably secured to its free 80 end and constructed to engage over the edge roll of a bath-tub.

In testimony whereof I affix my signature in presence of two witnesses. 85

JOHN REBEL.

Witnesses:

R. B. MOSER,
GEO. E. KRICKER.
